UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

COIN-CONTROLLED TELEPHONE PAY-STATION.

1,094,000.

Specification of Letters Patent. Patented Apr. 21, 1914.

Original application filed February 19, 1912, Serial No. 678,661. Divided and this application filed March 19, 1913. Serial No. 755,316.

To all whom it may concern:

Be it known that I, GEORGE A. LONG, a citizen of the United States, residing at Hartford, in the county of Hartford and State of Connecticut, have invented certain new and useful Improvements in Coin-Controlled Telephone Pay-Stations, of which the following is a specification.

This invention relates to coin controlled telephone pay stations. It should be understood that in using the term "coin" I do so with the object of not only including a piece of money but also with the object of including a check or something of an equivalent character.

The present case is a division of my application for patent for telephone pay stations, filed February 19, 1912, Serial No. 678,661, and which matured into Patent No. 1075485, Oct. 14, 1913.

A coin or check controlled telephone pay station involving my invention preferably includes in its make-up, a signal which may be of any suitable kind but which in the present case is of audible type, and a telephone transmitter, and although the transmitter and the signal may be related in any desirable manner, I prefer that they be in resonant connection, by reason of which when the signal is operated such fact will through said transmitter and line, be transferred to a central office operator to indicate to her that toll has been paid or some equivalent necessary act performed. The signal to which I have alluded may be operated in any suitable way, although I prefer that this be done by the person at the calling station or the individual who uses the pay station.

One of the primary objects of the invention is to provide means for preventing the operation of the signal until toll for a message has been paid.

The device possesses many other features of novelty and advantage, which with the foregoing will be set forth at length in the following description wherein I will outline in detail one of the many forms of embodiment of my invention, this showing being provided to enable those skilled in the art to practise the invention. From this it will be evident that I do not restrict myself to such showing; I may depart therefrom in several respects within the scope of the invention set

forth in the claims following said description. 55

In the organization thus shown, as soon as a coin has been introduced into the machine the signal mechanism may be released and operated. In addition to this I provide for several calls for one coin or it may be for a group of coins or for a given amount of money. The ordinary minimum charge for an outgoing local call is five cents. I provide for receiving a coin or coins of any denomination or denominations and to give in return for the amount a specific number of calls. In the present instance the machine is adapted to receive a twenty-five cent piece, and the person who inserts such coin into the machine will be entitled to five calls, although this will depend altogether on custom. 70

Referring to the drawings; Figure 1 is a front elevation partly in section, of a telephone pay station involving my invention. Fig. 2 is a vertical sectional view of the same. Fig. 3 is a view of the mechanism inclosed by the casing, and, Fig. 4 is a front elevation of an indicator. 75 80

Like characters refer to like parts throughout the several figures, which it will be perceived are on different scales.

The different parts of the device are preferably housed in a suitable casing such as 85 that denoted in a general way by 5, and to which is connected the telephone transmitter 6, after the usual fashion in this art. As already intimated the signal may be of any suitable kind; that shown is denoted in a 90 general way by 7 and consists of a gong in resonant connection with the said transmitter. This gong may be struck in any suitable manner for example by the hammer 8 on the forward stroke of the plunger 9, 95 which plunger extends through a hole or perforation in the casing 5 so as to be accessible exteriorly of said casing. It might be added that the plunger 9 is advanced, to effect the action of the hammer by the user 100 of the station and that it is retracted by a coiled spring 10 which with the gong and hammer are inclosed in the casing, being supported by the bracket 11. This bracket 105 11 also carries a register or counter 12, the plunger 9 having a lateral projection 13 adapted to enter between the branches of the fork 14 of an arm 14' connected with the

register to thereby operate said register on each forward movement of the plunger or equivalent manually-operable member. On the forward motion of the plunger 9 the hammer 8 is first swung out and then freed, at which point the operating spring for said hammer moves the latter quickly against the gong 7.

It is not a matter of importance as to what 10 the denomination of the coin or coins is, the object in the construction shown being to introduce into the machine a certain amount of money which prepays for a certain number of calls, and although it is conceivable 15 that several coins of different denominations might be simultaneously introduced into the machine, I have shown means for simply supplying one thereinto, and although as previously intimated the denomination 20 of this particular coin may vary, the parts are so proportioned as shown to receive a twenty-five cent piece. The means for receiving a coin or coins may vary as to construction, although that shown and now to 25 be described answers the necessary conditions.

In the casing 5 there are two coöperating members such as 15 and 16 which are adapted to be coupled by a coin or its equivalent, 30 the part 15 serving to operate certain devices within the casing as will hereinafter appear, while the part 16 is directly operable by the user of the machine. Unless a coin is employed to couple these two parts 35 the part 15 cannot be operated when the part 16 is, a coin being necessary to effect such action. The parts 15 and 16 might be aptly considered as skeleton cylinders, the casing 5 having interiorly thereof, means for 40 rotatively supporting the outer cylinder 16, the inner cylinder 15 being fitted within the said outer cylinder, and both having slots which normally register to receive the coin 17 which is adapted to be sustained temporarily by a rest as 18 carried by the outer cylinder. A runway as 19 leads to the normally registering slots in the parts 15 and 16 and from a slot 19' in one side of the casing 5. It will be supposed that a coin 45 is introduced into this runway. When it is, it travels down the same and enters the registering slots in the parts 15 and 16 thereby coupling said parts together so that they can be moved as one, by operating in the 50 present case, the outer cylinder or barrel 16 which latter it will be observed has an outwardly extending stud 20 supported for rocking motion in a bearing constituting part of the casing 5. Said stud is shown 55 equipped with a handle or lever 21 by which the same can be conveniently operated and which bears normally against a stop 22 on the casing at which time the slots of the two parts 15 and 16 coincide. The inner cylinder 60 15 is shown provided with an inwardly ex-

tending stud or pivot 23, the casing 5 interiorly thereof being provided with a bearing for supporting said stud 23 for turning movement. It follows that when the parts 15 and 16 are coupled together by a coin and that when the arm 21 is swung down otherwise operated, to impart a half turn to the outer cylinder or barrel 16, the inner barrel 15 is given a corresponding movement, and when the half turn has been completed the 7 coin 17 will drop from the two parts into the usual coin box 24 in the bottom portion of the casing 5.

The machine preferably includes indicating means which in the present case shows 8 both the amount of money that is in the machine and also the number of calls to which a subscriber may be entitled, although neither or both is essential. Although said indicating means may be of any convenient kind it is shown as comprising an indicating member such as 25 graduated from zero to 60, each graduation representing five cents or one call. In connection with the indicating member is a pointer or finger 26, the shank 9 of which extends through and moves longitudinally of registering slots 27 in the indicating member 25 and casing 5 respectively being connected with a carriage as 28 which in the present case has a movement transversely of the casing 5, being preferably operated as will hereinafter appear, in one direction through the primary agency 1 of the plunger 9 or its equivalent, and in the other direction through the primary agency 1 of the coin-controlled mechanism to which I have alluded already or in some similar manner. As shown this carriage is supported by parallel shafts 29 and 30 sustained by suitable bearings in the casing 1 and extending transversely thereof, the shaft 29 being shown as a screw while the shaft 30 is plain. Connected rigidly with the said carriage 28, is a nut 31 in engagement with the threaded portion of the screw 1 shaft 29, said nut fitting an opening in the carrier 28 and being held in place by the nut 32. The holding nut 32 engages the feed nut 31 at one end thereof, said feed nut having at the opposite end the pinion 33. From this it will be clear that when the feed nut 31 is moved longitudinally of the shaft 29 by rotating the latter, the carriage 28 will be similarly operated and at the same time will move longitudinally of the parallel supporting and guide shaft 30. In the construction shown the pinion 33 is in mesh with the gear 34 splined to the shaft 30 and the hub of which fits in the upper portion of the said carriage 28 and is held in place by the nut 35. Pinned or otherwise suitably connected with the stud 23 is a gear 36 in mesh with the pinion 37 fastened suitably to one end of the shaft 38 supported by bearings in the casing 5. This 1

shaft 38 also carries the gear 39 in mesh with the pinion 40 on one end of the screw shaft 29. Suitably fastened to the shaft 30 is a ratchet wheel 41 engageable by the pawl 42 pivotally carried by the rocker 43 loosely carried by the shaft 30. To the rocker is shown loosely connected the arm 44 fastened in some suitable manner to the rock shaft 45 to which is also rigidly connected 10 the arm 46 connected by a loose joint to the inner end of the plunger or equivalent member 9.

It will be assumed that a twenty-five cent piece 17 has been inserted in the machine 15 and is resting on the support 18, and that the members 15 and 16 are, therefore, coupled together by such coin. In this event said parts 15 and 16 can be operated as one by the handle 21, and on such movement 20 the said parts 15 and 16 will be given a half rotation and when they are inverted the quarter 17 will gravitate therefrom and thereby uncouple said parts. It will be understood that although the inner cylinder 25 has a continuous step-by-step movement always in the same direction, that the outer cylinder is capable simply of a half turn, being limited by the stop 22 already described and the companion stop 21'. On 30 the turning of the inner cylinder 15 the stud 23 is given a similar movement, and the screw shaft 29 through the interposed gearing already described is correspondingly moved whereby the carriage 28 will be advanced or as shown, moved to the right 35 in Figs. 1 and 3. If prior to the operation already described the pointer 26 was opposite zero on the indicating member or scale 25, said pointer at the conclusion of said operation 40 would be opposite the five mark. If a second quarter were introduced the pointer through the movement of the carriage and the parts already described, would be carried to the ten mark on the pointer 45 and so on, so that if twelve quarters were employed the pointer would finally be opposite the sixty mark, indicating that \$3.00 was in the machine, and in such a case the carriage 28 would be shifted to the extreme 50 advanced position and would remain in this position or in any intermediate advanced position until the signal 7 was operated on making a call.

It will be assumed that coin is in the machine 55 and that a call is to be made. In making a call the central office operator requires the subscriber to operate the signal, and before the signal can be operated it is necessary to thrust the plunger 9 rearward. 60 On such motion of the plunger the pawl 42 through the intermediate described parts is moved one step thereby imparting a corresponding movement to the ratchet wheel 41 and therefore rotating the shaft 30. On 65 said movement of said shaft the gear 34 and

hence the gear 33 and nut 31 will be similarly operated so as to retract said nut 31 and therefore the carriage 28, the latter being retracted or drawn backward one step and consequently moving the pointer 26 70 from a higher toward a lower number on the scale 25. If the pointer happened to be opposite the five mark on the scale, the same would be moved opposite the four mark on said scale, when the operation just described was concluded. It will be assumed that there is twenty-five cents in the machine. When each call is made the carriage 28 is retracted one step, and when the five calls have been made the gear 34 will be brought substantially and solidly against the hub of the gear 41 so as thereby to effectually lock the ratchet 41 against movement and therefore prevent the plunger 9 from being moved to effect the operation 85 of the signal 7, it being necessary to insert a coin before the signal mechanism can be operated.

I have described in detail the construction shown in the accompanying drawings, 90 which is highly advantageous. I wish to make it clear that I can depart from this construction in many respects. I may if desired provide means for handling coins of different denominations. 95

Although the counter or register 12 is desirable, it like certain other parts already described, may in some cases be omitted and in similar manner equivalents may be employed instead of certain of the members 100 already described within the scope of my invention. A register or counter, however, is advantageous in that a check is had upon the subscriber, so that the subscriber must of necessity pay for the calls which have 105 been registered, notwithstanding the fact that a slug or slugs may have been used in obtaining one or more of such calls.

While I have termed my invention a "coin controlled telephone pay station," it is not 110 impossible that I might use some or all of the features in connection with other kinds of apparatus.

What I claim is:

1. The combination of a signal, an indicator, coin controlled means for advancing said indicator to a degree proportionate with the amount of money employed in the operation of said coin controlled means, and signal operating mechanism having means 115 for retracting said indicator. 120

2. The combination of an indicator, coin controlled means for advancing said indicator varying distances and in proportion with the amount of money employed in operating said coin controlled means, a signal, and signal operating mechanism having means for retracting said indicator. 125

3. The combination of coin controlled means advanceable to various extents and in 130

proportion with the amount of money utilized in the operation thereof, an indicator advanceable with the coin controlled means, a signal, and mechanism for intermittently retracting the coin controlled means, each intermittent movement being a fraction of the amount of advancing movement, said mechanism having means for operating said signal on each of said intermittent movements and for also retracting the indicator.

4. The combination of a telephone transmitter, an audible signal in resonant connection with the transmitter, an indicator, coin controlled means for advancing said indicator to a degree proportionate with the amount of money employed in the operation of said coin controlled means, and signal

operating mechanism having means for retracting said indicator.

5. The combination of an audible signal, 20 a telephone transmitter to receive the sounds of said signal, an indicator, coin controlled means for advancing said indicator to a degree proportionate with the amount of money employed in the operation of said 25 coin controlled means, and signal operating mechanism having means for retracting said indicator.

In testimony whereof I affix my signature in presence of two witnesses.

GEORGE A. LONG.
